[57] CLAIM

The ornamental design for finger ring, as shown and described.

DESCRIPTION

FIG. 1 is a perspective view of a finger ring showing my new design;

FIG. 2 is a top plan view thereof, the bottom plan view being a mirror image thereof;

FIG. 3 is a side elevational view thereof, the opposite side being a mirror image thereof;

FIG. 4 is a front elevational view thereof; and,

FIG. 5 is a rear elevational view thereof.

It being understood that the angel figure lies on the flat plane of the finger ring beneath the transparent stone.
